DESIGN FOR KNITTED FABRIC

Alexander Grodnick, Weehawken, N. J.

Application January 15, 1938, Serial No. 74,320

Term of patent 3½ years

To all whom it may concern:

Be it known that I, Alexander Grodnick, a citizen of the United States and residing at Weehawken, in the county of Hudson and State of New Jersey, have invented a new, original, and ornamental Design for Knitted Fabric, of which the following is a specification, reference being had to the accompanying drawing, forming part thereof, and in which the figure shows a plan view of the knitted fabric embodying the invention.

The design comprises a knitted fabric consisting of uniformly spaced, square blocks of ribbed texture arranged in vertical and horizontal rows on the specific mesh background, as shown.

I claim:

The ornamental design for knitted fabric, substantially as shown and described.

ALEXANDER GRODNIK.
